TEA BAG TONG

Arvid M. Sundquist, 617 N. State St., Elgin, Ill.

Filed Feb. 26, 1963, Ser. No. 73,721

Term of patent 7 years

(Cl. D44—4)

FIG. 1 is a top plan view of a tea bag tong showing my new design;

FIG. 2 is a bottom plan view thereof;

FIG. 3 is a side view thereof;

FIG. 4 is a view of one end thereof; and

FIG. 5 is a view of the other end thereof.

I claim:

The ornamental design for a tea bag tong, substantially as shown.
